UNITED STATES PATENT OFFICE.

FREDERICK HENRY ROYCE, OF WEST WITTERING, NEAR CHICHESTER, ENGLAND, AS-
SIGNOR TO ROLLS-ROYCE LIMITED, OF DERBY, ENGLAND.

IGNITION DEVICE OF INTERNAL-COMBUSTION ENGINES.

Application filed October 27, 1925, Serial No. 65,260, and in Great Britain November 19, 1924.

This invention relates to a centrifugal device for automatically adjusting the advance and retard device of the ignition in an internal combustion engine and is an improvement on or modification of my invention for which a British patent has been granted to me dated the 16th day of February, 1922 and numbered 198,014. This invention is useful where in lieu of the member to be moved by the centrifugal device being a shaft co-axial with the rotating shaft which carries the centrifugal device as in the original patent, the member to be moved is a sleeve sliding axially on the said rotating shaft.

The invention applies to constructions in which the centrifugal device is supported on two opposite trunnions extended from a rotating shaft, and consists of four weights the centres of gravity of which stand in relation to one another as the corners of a square or rectangle, the pairs of weights in diagonal relationship being rigidly secured together, and all the weights swinging about a centre with a spring or springs reacting between each pair of weights torsionally and not otherwise.

The object of this invention is to improve the sensitiveness of such type of apparatus and, to that end, to effect improvements in the method of mounting and adjusting the springs re-acting between the centrifugal weights, consisting in arranging two sleeves, one superimposed on the other, mounted on each of the trunnions respectively rigidly attached to the bars carrying the respective pairs of weights and a coil spring winding each pair of sleeves, having a torsional tension thereon, one end of which is secured to a bar carrying two of the weights, or the sleeve rigid therewith, and the other end is secured to the bar carrying the other two weights, or the sleeve rigid therewith, and further consisting of improved transmission from the centrifugal weight to the lever operatively connected to the advance and retard device.

An example of my invention is illustrated in the accompanying drawings.

Fig. 1 is a central view partly elevation and partly section through the axis of the shaft carrying the centrifugal device. Figs. 2, 3 and 5 are horizontal sections on the lines of Fig. 1 marked respectively 2-2, 3-3,

and 5-5 and Fig. 4 is a side view of the 55 centrifugal device.

a is the case supporting the centrifugal apparatus having a flange *a*¹ which rests on the flange *a*² of the engine crankcase, to which it is secured by means of perforated 60 bosses *a*³ and bolts *a*⁴. *a*⁵ and *a*⁶ are covers secured to the case *a* and *a*⁷ is a sleeve with an extended skirt secured to the shaft hereinafter referred to, the covers *a*⁵, *a*⁶, and sleeve *a*⁷ being shaped to form an oil seal 65 or trap. *a*⁸ is a threaded nut engaging a threaded extension *a*⁹ of the case *a* holding in position the outer race of the ball bearings hereinafter referred to. *b* is the shaft carrying the centrifugal weights rotating in 70 ball bearings *b*¹. *b*² is a conical sleeve, which with a shoulder formed on the shaft, locates axially the inner race of the said ball bearings and is fixed for rotation to the shaft *b*. *b*³ is a sleeve carrying the pinion 75 *b*⁴ (by means of which the shaft is driven) fixed for rotation with sleeve *b*² having a recess *b*⁵ formed at the end thereof, and secured to the shaft by the washer *b*⁶ and nut *b*⁷. *b*⁸ is a washer to determine the axial 80 location of the assembly. *c* is a sleeve pinned to the shaft *b* and has formed on it trunnions *c*¹ and *c*² which constitute the spindles or axles of the centrifugal device. *d*¹ and *d*¹¹ are two bars mounted on the trunnion *c*¹ having relation to one another as the lines of the letter X, and *d*² and *d*²² are corresponding bars mounted on the other trunnion *c*² in like manner. *d*³ are weights of the centrifugal device located between the 90 bars *d*¹ and *d*¹¹ on the one side and *d*² and *d*²² on the other side, and secured thereto by means of bolts *d*⁴ passing through perforations in the bars and weights and engaged by the nuts *d*⁵. The weights are further secured in the desired position by 95 tongues *d*⁶ formed on the arms and engaging recesses formed on the weights. *d*⁷ are lugs formed on the bars *d*¹, *d*¹¹, *d*² and *d*²² for the purposes hereinafter described. *e* is a sleeve 100 slidably axially on the shaft, and *e*¹ are two washers held apart by the spacer sleeve *e*² and located axially on the sleeve *e* by the shoulder *e*⁴ and a nut *e*⁵ engaging a thread on the end of the sleeve *e*. Between the 105 washers is freely mounted an annular member *e*⁶ formed with lugs *e*⁷ with holes *e*⁸ drilled therein. *e*⁹ are lugs formed on the

sleeve e for the purposes hereinafter appearing. f is a lever formed with a boss f^1 rocking on a spindle f^2 . f^3 are jaws embracing the annular member e^6 with a round hole 5 therein to fit on the end of the lever f to which it is secured by set screw f^4 passing through a perforation in the jaws and lever, and engaging a thread in the farther side of jaws, the jaw-piece being split at that point, 10 in the plane of the paper on Fig. 2. The jaws are formed with threaded eyes which register with the holes e^8 and are located on the lugs e^7 by set screws f^5 which are secured from rotation by a tab washer f^6 . g are 15 four links secured at the lower end to lugs d^7 and located in relation to one another by the sleeve g^1 formed with shoulders g^2 and the ends of which pass through perforations in the links and are riveted over on the outside. 20 The sleeves and links are located in relation to, and are secured to, the bars by means of a shouldered bolt g^3 and the shouldered distance sleeve g^4 , the ends of the bolt g^3 and of the sleeve g^4 being passed through perforations in the bars and riveted over on the outside. The said links at the upper end 25 are secured to lugs e^9 by rivets g^5 passing through perforations in the said links and lugs and riveted over on the outside. h^1 and h^2 are flanged bushings mounted on the trunnions c^1 and c^2 and resting against shoulders formed on the sleeves c with extensions h^{11} and h^{22} which are threaded at the ends 30 for the purpose hereinafter described. h^3 and h^4 are flanged bushes mounted respectively on the bushes h^1 and h^2 . The bar d^2 is mounted on the bush h^3 and is secured thereto from rotation. The bar d^{11} is likewise mounted on and secured to the bush h^1 35 and bar d^2 is likewise mounted on and secured to bush h^2 , and the bar d^{22} is likewise mounted on and secured to bush h^4 . h^5 are two spiral springs respectively secured at one end to the bars d^1 and d^{22} and secured at the other ends to the bushes h^1 and h^2 by means now to be described. h^6 are 40 collars each carrying a pin or hook h^7 to which the end of one of the springs is secured, the said collars respectively rest on a shoulder of the bushes h^1 and h^2 . h^8 are washers secured from rotation on the said bushes, and h^9 are nuts engaging the threads at the end of the bushes. The springs have no axial tension but only a torsional tension 45 and that to the degree required. The adjustment of the torsional tension of each spring is brought about by rotating the collar which carries with it one end of the spring until the desired tension is attained, and then screwing up the nut thus causing the nonrotatable washer to impinge on the collar and clamp the same against the shoulder upon which it rests. 50

With apparatus as described the centrifugal device is perfectly balanced and is

practically free from all reactions or forces tending to load the bearings of the moving parts.

What I claim is:—

1. Apparatus to automatically adjust the advance and retard device of an internal combustion engine comprising a centrifugal device attached to and rotating with a shaft driven by the engine, consisting of four centrifugal weights, of which the respective centres of gravity stand in relation to one another as the corners of a square or rectangle, the pair of weights diagonally opposite being respectively connected or held by two bars or arms, the two bars connecting two elements or weights necessarily crossing the bars connecting the other two, the two bars of each pair being respectively supported and rocking on two oppositely placed trunnions projecting from the shaft 75 at right angles thereto; a sleeve slidable on said shaft means including links pivotally hinged to such bars and to the sleeve whereby the movement of the weights causes an axial movement of the sleeve on the 80 shaft, a spark control lever pivoted intermediate its ends and having one of said ends pivotally and slidably connected to said sleeve; and an elastic device comprising a sleeve mounted on each of the trunnions to 85 which the inner bars are respectively rigidly secured, a sleeve mounted on each of the said sleeves to which the outer bars are respectively rigidly secured the inner sleeves extending beyond the outer sleeves, coil springs 90 with torsional tension therein embracing each of the outer sleeves fixed at one end to the outer bar or a member rigid therewith and fixed at the other end to the inner sleeve. 95

2. Apparatus to automatically adjust the advance and retard device of an internal combustion engine comprising a centrifugal device attached to and rotating with a shaft driven by the engine, consisting of four centrifugal weights, of which the respective centres of gravity stand in relation to one another as the corners of a square or rectangle, the pairs of weights diagonally opposite being respectively connected or held by two bars, the two bars connecting two elements or weights necessarily crossing the bars connecting the other two, the two bars of each pair being respectively supported and rocking on two oppositely placed trunnions 100 projecting from the shaft at right angles thereto means including links pivotally hinged to such bars and to the sleeve whereby the movement of the weights causes an axial movement of a slidable sleeve mounted on the shaft, a spark control lever pivoted intermediate its ends and having one of said ends pivotally and slidably connected to said sleeve, and an elastic device comprising a sleeve mounted on each of the trunnions 105 110 115 120 125 130

to which the inner bars are respectively rigidly secured, a sleeve mounted on each of the said sleeves to which the outer bars are respectively rigidly secured, the inner sleeves extending beyond the outer sleeves and having threaded ends, a collar freely mounted on the ends of each of the inner sleeves and seating against a shoulder formed thereon, with a hook or pivot on such collar to which the end of the coil spring can be secured, a washer mounted on the end of each of the inner sleeves with a non-rotatable device, a coil spring with torsional tension therein embracing each of the outer sleeves secured at one end to the outer bar or a member rigid therewith and at the other end to the said collar, and nuts engaging the threads on the inner sleeves whereby on loosening the nut the collar can be rotated to adjust the tension of the spring and on screwing up the nut the adjustment is retained.

3. Apparatus as claimed in claim No. 1 the means comprising two links respectively pivotally hinged to two lugs on opposite sides of the sliding sleeve and to the bars of the centrifugal device.

4. Apparatus as claimed in claim No. 1 the means comprising two links respectively hinged at one end on pivots or bolts traversing the pairs of bars of the centrifugal device, and centrally located thereon by a shouldered bolt or pivot and by riveted distance pieces, and at the other end secured to two lugs on the sliding sleeve by rivets substantially as described.

5. Apparatus as claimed in claim No. 1 the sliding sleeve being geared to one of the arms of said spark control by means of a

flange formed on such sleeve, two washers with a cylindrical distance piece of smaller diameter between them (thus forming an annular channel between them) fitted and threaded on the sleeve, and located at one end by the flange and at the other end by a nut engaging a thread on the sleeve, an annular member loosely mounted between such washers with a clearance between it and the cylindrical distance piece and having two opposite trunnions extended therefrom, and the arms of the said lever being in the form of jaws, embracing the annular member and hinged to the trunnion.

6. Apparatus as claimed in claim No. 1 the sliding sleeve being geared to one of the arms of said lever, by means of a flange formed on such sleeve, two washers with a cylindrical distance piece of smaller diameter between them (thus forming an annular channel between them) fitted and threaded on the sleeve and located at one end by the flange and at the other end by a nut engaging a thread on the sleeve, an annular member loosely mounted between such washers with a clearance between it and the cylindrical distance piece and having two opposite trunnions extended therefrom, and the arms of the said lever being in the form of jaws, embracing the annular member the jaws terminating in eyes internally threaded the trunnions having holes drilled axially, and set screws partially threaded, the threaded part engaging the said eyes and the other part engaging the said holes.

In witness whereof I have signed this specification.

FREDERICK HENRY ROYCE.
